STOCKING

Isidor Rabinowitz, Philadelphia, Pa.

Application July 14, 1953, Serial No. 25,945

Term of patent 14 years

(Cl. D47—7)

To all whom it may concern:

Be it known that I, Isidor Rabinowitz, a citizen of the United States, residing in the city of Philadelphia, State of Pennsylvania, have invented a new, original, and ornamental Design for a Stocking, of which the following is a specification, reference being had to the accompanying drawing, forming a part thereof, wherein the figure is a rear perspective view of a stocking, showing my new design.

The front of the stocking is conventional.

I claim:

The ornamental design for a stocking, as shown and described.
